UNITED STATES PATENT OFFICE

104,029

DESIGN FOR A FACE BRUSH

Jacqueline Gray, Chicago, Ill.

Application September 21, 1936, Serial No. 64,939

Term of patent 14 years

To all whom it may concern:

Be it known that I, Jacqueline Gray, residing at Chicago, in the county of Cook and State of Illinois, a citizen of the United States, have invented a new, original, and ornamental Design for a Face Brush, of which the following is a specification, reference being had to the accompanying drawing forming a part thereof.

I claim:

The ornamental design for a face brush substantially as shown.

JACQUELINE GRAY.
